Heat treatable aluminum alloys of increased mechanical strength are produced by submitting the alloy to a solution and quenching treatment followed by a combination of plastic deformations and precipitation hardening, including a first aging treatment at a temperature not higher than 200°C, a plastic deformation and then a further aging at a temperature not lower than the first, the combination for deformations and hardenings being a cycle repeatable on the alloy.

THERMOMECHANICAL TREATMENT PROCESS FOR HEAT TREATABLE ALUMINIUM ALLOYS

The present invention concerns a thermomechanical process particularly suitable to achieve a remarkable increase in the mechanical strength of semifinished heat treatable aluminum alloys without negatively affecting the secondary properties thereof.

This invention particularly comprises specific thermomechanical treatments specially suitable for aluminum alloys of the system Al-Zn-Mg; Al-Zn-Mg-Cu; Al-Cu; Al-Cu-Mg; Al-Cu-Mg-Si; Al-Si-Mg; said alloys being particularly useful for the aeronautical and motor industries as well as, more extensively for constructional parts requiring high mechanical strength. The improvements in the alloy properties can be attained, according to the present invention, through thermomechanical cycles based on suitable combinations of plastic deformations and hardening by precipitation; by these treatments it is in fact possible to induce in the materials a condition of super-hardening related to the combined effect of the hardening phases and of a stable structure of a dislocation network induced by the deformation.

The thermomechanical cycle according to the present invention substantially differentiates from the combined cycles deformation and aging suggested for heat treatable Al alloys by prior art disclosures both in consequence of the different sequence of the various phases making up a thermomechanical cycle and also owing to the particular temperatures used for some intermediate phases; the sequence of phases according to this invention allows in fact one to obtain, particularly for some kinds of alloys, better combinations of static strength and secondary characteristics by virtue of the fact that a real super-hardening condition, unobtainable through the known thermomechanical cycles, is induced in said alloys.

Particularly, the known combined treatments so far used for Al alloys of the systems Al-Cu-MG, Al-Cu, Al-Si-Mg and Al-Zn-Mg-Cu do not lead to such results as are obtainable through the herein proposed sequence of cycles, since said known treatments do not induce any superhardening condition characterized by high structural stability.

An object of the present invention is to provide a particular thermomechanical process suitable to induce in said heat treatable Al alloys a super-hardening such as to grant them remarkable improvements in their static strength characteristics without negatively influencing the other properties of said alloys.

Another object of the present invention is to provide a process which, by establishing such a super-hardening, succeeds in improving some secondary characteristics of said alloys without significantly altering other secondary characteristics while always producing a static mechanical strength not below but often above that obtainable on the same alloys through traditional treatments.

These objects are advantageously reached through a thermomechanical process suited to induce in the heat treatable Al alloys a super-hardening characterized by its high structural stability, said process according to this invention comprising submitting said aluminum alloys, preferably in the form of bars, sheets plates and like preformed shapes to a solution and quenching (T)

5 treatment in water or blast air, followed by a combination of plastic deformations and precipitation hardenings including: a first aging treatment (A₁) at temperature below 200°C, for a time not longer than 50 hours, a plastic deformation (H), preferably a thickness or section reduction and then a further aging (A₂) at a temperature and for a time preferably not smaller than the ones used for said first aging treatment, said combination of deformations and hardenings (A₁HA₂) making up a treatment cycle repeatable — at temperatures and for times preferably different from the mentioned ones — on the same alloy sample, for further improving its mechanical properties.

10 More particularly said thermomechanical process comprises for the alloys having Cu as the main alloying element, a plastic deformation (H) not below 5 percent, after said quenching treatment (T). The general scheme of the thermomechanical treatment which is 15 within the scope of this invention and applicable to heat treatable Al alloys, is of the type: TA₁HA₂; TA₁HA₂HA₃... or type THA₁HA₂; THA₁HA₂HA₃... wherein

20 T stands for a solution (performed at various temperatures and for different heating times) and quenching carried out in various media and at various cooling rates,

25 A₁ represents an aging treatment developed (through one or more stages, at various temperatures and for different heating times) till obtaining in the material a distribution of precipitated or pre-precipitated zones, coherent and/or semi-coherent, with a stability degree such as to obtain the effectiveness of the selected thermomechanical cycle in its following stages,

30 H stands for a plastic deformation brought about, with cold or warm processing, in a way and at values such as to let the material acquire high density and homogeneous distribution of dislocations network while retaining also, after its deformation, the possibility of a following hardening due to aging.

35 A₂A₃... etc. represent intermediate or final steps of aging carried out at selected temperature and through suitable times, in such a way as to induce in the material a composed structure of dislocations and of a final precipitation hardening as favorable as possible for the final characteristics wished for the material.

40 It has in practice been found that any semifinished product of heat treatable Al alloy of commercial type can be advantageously treated with the process according to this invention; it has been also found that the best results are obtained when the concerned process is applied to semifinished materials coming from ingots or plates submitted to particularly strong cycles of homogenization, as well as when this process is applied to semifinished material coming from alloys prepared with high purity Al and from alloys containing particular additional elements, mainly when said semifinished materials are submitted to strong homogenization cycles.

45 The thermomechanical process according to this invention is particularly suitable for treating Al alloys of the type: Al-Zn-Mg; Al-Zn-Mg-Cu; Al-Cu, Al-Cu-Mg; Al-Cu-Mg-Si; Al-Si-Mg.

To better evidence the results obtainable through this process, some examples of treatment of Al alloys are given hereinafter for illustration only and are not to be construed as limiting of the invention in scope.

In addition to the treatment of this invention, known treatments are also reported in said examples, and included tables, to better evidence the remarkable improvements obtained in the final characteristics of the materials.

It is also to be noted that in said examples the known treatments are carried out using the best known conditions for obtaining the best results in properties, so that these results can be compared with the results of the cycles according to this invention.

In said examples:

R_m is the mechanical tensile strength, in kg/mm^2

R_p (0.2) is the permanent deformation limit load, in kg/mm^2

A_5 stands for the ultimate elongation, in percent.

EXAMPLE 1

Five rolled sheets (thickness = 5 mm) of commercial alloy with composition Al—5.1% Zn — 1.1% Mg — 0.14% Cr — 0.21% Mn — 0.12% Zr — 0.12% Fe — 0.10% Si were submitted to quenching (after pre-heating at 460°C for 1 hour) in water at room temperature, every sheet treated in this way being afterwards submitted to a different thermal or thermomechanical cycle. Said cycles, each for every sheet, were as follows:

TA (known cycle - isothermal (one step) aging)

TA₁A₂ (known cycle -di-isothermal (two step) aging)

THA₁A₂ (known cycle)

TA₁A₂H (known cycle)

TA₁HA₂ (cycle according to this invention)

wherein H represents a 20 percent reduction in thickness obtained through rolling at room temperature, parallel to the original rolling direction

Mechanical tensile tests were carried out along the rolling direction corresponding to the hardness peaks of every treatment cycle and the ascertained results are shown in the following table 1.

TABLE 1

Cycle	Treatment				Mechanical Properties			
	A ₁ Temp (°C)	A ₁ Time (hours)	A ₂ Temp (°C)	A ₂ Time (hours)	R _m Kg/mm ²	R _p (0.2) Kg/mm ²	A ₅ %	
TA ₁	100	200	—	—	40.1	34.8	16.5	
TA ₁ A ₂	100	10	130	22	38.4	33.7	17.0	
THA ₁ A ₂	100	10	130	22	34.9	31.8	13.3	
TA ₁ A ₂ H	100	10	130	22	44.8	43.2	6.8	
TA ₁ HA ₂	100	10	100	120	44.3	42.2	12.4	

This table clearly evidences that cycle TA₁HA₂, according to the present invention, gives the best results and particularly the highest combination of strength and ductility.

EXAMPLE 2

Two portions of commercial plate of 35 mm thickness with composition Al — 4.35% Zn — 2.06% Mg — 0.15% Cr — 0.22% Mn — 0.10% Zr — 0.17% Fe — 0.15% Si were submitted to a solution treatment at

60

65

460°C for two hours under steady conditions; one sample was then drastically quenched in cold water (T), while the other was quenched in a stream of air (Ta.v.).

Three samples of the first portion previously treated in cold water, were submitted to thermal and thermomechanical (one for every specimen) treatments according to the following cycles: TA₁A₂ — TA₁HA₂ — TA₁HA₂ while three further samples of the second portion, previously treated in an air stream, were submitted to treatments (one for every sample) of the type: Ta.v.A₁A₂ — Ta.v.A₁HA₂ — Ta.v.A₁HA₂.

H represents a 20 percent plastic deformation (thickness reduction) brought about on each of the six samples by rolling them, at room temperature, parallel to the direction of the original working.

Specimens were taken from the long transverse direction of said samples, to ascertain mechanical characteristics (R_m , R_p and A_5) and stress corrosion resistance (by continuous dip in a 3% NaCl solution buffered at pH = 5.2, being the tensile stress applied to the specimen equal to 75 percent of R_p (0.2)). The following Table 2 shows the results which were obtained:

TABLE 2

Cycle	Treatment				Mechanical Properties			Average time for stress corrosion failure Hours
	A ₁ Temp (°C)	A ₁ Time (hours)	A ₂ Temp (°C)	A ₂ Time (hours)	R _m (Kg/mm ²)	R _p (0.2) (Kg/mm ²)	A ₅ %	
TA ₁ A ₂	100	10	130	22	43.4	40.1	7.7	88
TA ₁ HA ₂	100	10	130	6	45.0	43.0	7.5	113
TA ₁ HA ₂	100	10	130	22		40.8	6.8	208
Ta.v.A ₁ A ₂	100	10	130	22	40.6	36.4	8.0	>1000
Ta.v.A ₁ HA ₂	100	10	130	6	42.5	40.5	6.8	>1000
Ta.v.A ₁ HA ₂	100	10	130	22	40.9	38.5	6.5	>1000

The table clearly evidences that both thermomechanical cycles TA₁HA₂ and Ta.v.A₁HA₂ being within the present invention, lead to remarkable improvements.

In case of water cooling the stress corrosion resistance is improved without involving any decrease in the mechanical properties of the material. In case of air stream/cooling a stress corrosion resistance equal to the one attained through known treatments is maintained but the mechanical properties are improved.

EXAMPLE 3

Two extruded rod portions (diameter = 15.2 mm) of commercially produced alloy consisting of Al — 5.07% Zn — 0.96% Mg — 0.14% Cr — 0.22% Mn — 0.12% Zr — 0.13% Fe — 0.10% Si were submitted to quenching (after preheating for 2 hours at 460°), in water at room temperature and subsequently underwent two different thermal and thermomechanical cycles (a cycle different for every rod portion) of the type TA₁A₂ and TA₁HA₂, wherein H stands for a 20

percent deformation given by drawing at 25°C abt. Some specimens were taken from the two portions treated as above, and submitted to mechanical tensile strength tests and rotating cantilever fatigue tests (un-notched specimens): the specific results obtained thereby are shown in the following Table 3.

TABLE 3

Cycle	Treatment				Mechanical properties			Fatigue characteristics		
	A ₁ (°C)	Temp (°C)	H (%)	A ₂ (°C)	Temp (°C)	Rm Kg/mm ²	Rp (0.2) Kg/mm ²	A ₅ (%)	Number of cycles (n)	Breaking stress (σ) Kg/mm ²
TA ₁ A ₂	100	12	—	150	12	43.7	39.9	10.2	10 ⁵	30.0
									10 ⁵	24.0
									10 ⁷	21.5
									10 ⁸	21.0
TA ₁ HA ₂	100	15	20	115	15	52.4	51.5	6.0	0 ⁵	31.0
									10 ⁶	25.0
									10 ⁷	21.5
									10 ⁸	20.0

By the shown data it is seen that the cycle according to this invention highly increases the static strength characteristics, in comparison with a traditional cycle TA₁A₂. It is also to be noted that the fatigue characteristics displayed by material treated according to TA₁HA₂ are substantially analogous to those noticed on material treated according to TA₁A₂.

EXAMPLE 4

Six rolled strips (thickness — 2 mm) of commercially produced Al alloy having composition Al — 5.5% Zn — 2.5% Mg — 1.7% Cu — 0.20% Mn — 0.13% Cr — 0.28% Fe — 0.20% Si — 0.08 Ti — were submitted to quenching in water at room temperature (after pre-heating for one hour at 460°C), followed by various thermal and thermomechanical treatment cycles (a different cycle for every strip) of the type TA₁ — TA₁A₂ — TA₁HA₂ — TA₁HA₂ — TA₁H — — TA₁H₁A₂H₂A₃, wherein H represents a deformation (given by rolling at 25°C and 150°C abt.) produced by working parallel to the original rolling direction, said deformation amounting to 10 percent, 20 percent, 30 percent.

Tensile tests (being the specimen axis parallel to the original rolling direction) were carried out corresponding to the hardness peaks of every treatment cycle and the results obtained appear in the following Table 4:

TABLE 4

Cycle	Treatment				Mechanical properties			
	A ₁ (°C)	Temp (hours)	H ₁ (%)	A ₂ (°C)	Temp (°C)	Rm Kg/mm ²	Rp (0.2) Kg/mm ²	A ₅ (%)
TA ₁	120	24	—	—	—	58.5	51.5	13.1
TA ₁ A ₂	105	6	—	120	24	59.3	52.3	13.9
TA ₁ HA ₂	105	6	30	105	20	67.0	64.7	7.7
TA ₁ HA ₂	105	6	20	120	8	64.5	60.0	8.0
TA ₁ H	120	24	20	—	—	67.1	64.5	4.0
TA ₁ H ₁ A ₂ H ₂ A ₃						67.4	66.0	7.1

The values used for the last cycle in Table 4, (TA₁H₁A₂H₂A₃), were: A₁ = 105°C for 6 hours, H₁ = 20%, A₂ = 105°C for 6 hours, H₂ = 10%, A₃ = 105°C for 15 hours.

EXAMPLE 5

Two sheets (thickness = 2 mm) were rolled from a chill cast ingot (of 110 mm diameter) (cooled in water after casting) of composition Al — 8.02% Zn — 2.52% Mg — 1.58% Cu — 0.20% Mn — 0.18% Zr — 0.002%

TABLE 6

Cycle	Treatment				Mechanical Properties		
	A ₁ Temp (°C)	Time (hours)	A ₂ Temp (°C)	Time (hours)	Rm Kg/mm ²	Rp (0.2) Kg/mm ²	A _s %
TA ₁	140	30	—	—	47.5	39.3	11.0
TA ₁ HA ₂	140	10	140	10	49.0	45.2	8.5

This table evidences a remarkable increase in the yield strength as well as a very slight decrease in the elongation attained with the cycle of this invention, in comparison with the results reached through conventional cycle TA₁; it is therefore quite evident that the combination of properties obtained through the cycle of this invention is superior.

EXAMPLE 7

Rolled sheets (thickness = 2 mm) of commercially produced alloy Al — 4.5% Cu — 1.5% Mg — 0.56% Mn — 0.33% Fe — 0.14% Si, were submitted, after quenching in room temperature water (previous pre-heating for one hour at 495°C) to various thermal and thermomechanical cycles of the type TA₁ — THA₁ — TA₁H — TA₁HA₂ — TH₁A₁H₂A₂ wherein H represents a deformation obtained by rolling at 25°C, parallel to the original rolling direction. The tensile tests (performed with specimen axis parallel to the rolling direction) are shown in following Table No. 7.

TABLE NO. 7

	Treatment	Rm Kg/mm ²	Rp (0.2) Kg/mm ²	A _s %
Type TA ₁	A ₁ =190°C for 10 hours	48.6	40.2	14.5
Type THA ₁	A ₁ =190°C for 8 hours H = 6% (obtained by cold rolling)	53.7	52.9	8.1
Type THA ₁	H=40% (obtained by cold rolling) A ₁ = 190°C for 2 hours	58.2	56.2	6.6
Type TA ₁ H	A ₁ = 190°C for 10 hours H = 40% (obtained by cold rolling)	58.9	56.7	3.5
Type TA ₁ HA ₂	A ₁ = 140°C for 8 hours H = 40% (obtained by cold rolling) A ₂ = 140°C for 8 hours	60.9	54.6	11.4
Type TA ₁ HA ₂	A ₁ = 140°C for 6 hours H = 20% (obtained by cold rolling) A ₂ = 180°C for 4 hours	56.1	51.8	12.6
Type TH ₁ A ₁ H ₂ A ₂	H ₁ = 6% (obtained by cold rolling) A = 140°C for 12 hours H ₂ = 20% (obtained by cold rolling) A ₂ = 140°C for 20 hours	58.4	51.9	13.4

EXAMPLE NO. 8

Rolled sheets (thickness = 2 mm) of commercially produced alloy Al — 0.98% Si — 0.73% Mg — 0.62Mn — 0.27% Fe, were submitted (previous quenching car-

ried out after steady preheating of 1 hour at 530°C and cooling in water at room temperature) to various thermal and thermomechanical cycles of the type TA₁ — TA₁H — TA₁HA₂ wherein H represents a deformation given by rolling, at 25°C abt., parallel to the original direction of working.

The tensile tests (performed with the specimen axis parallel to the rolling direction) are shown in following Table No. 8.

TABLE 8

	Treatment	Rm Kg/mm ²	Rp (0.2) Kg/mm ²	A _s %
15	Type TA ₁	A ₁ = 175°C for 8 hours	37.1	34.5
15	Type TA ₁ H	A ₁ = 160°C for 10 hours H = 20% (obtained by cold rolling)	37.0	34.0
20	Type TA ₁ HA ₂	A ₁ = 100°C for 50 hours H = 40% (obtained by cold rolling) A ₂ = 150°C for 10 hours	41.0	38.0
25	Type TA ₁ HA ₂	A ₁ = 150°C for 4 hours H = 40% (obtained by cold rolling) A ₂ = 150°C for 2 hours	43.9	41.8

The above given examples clearly demonstrate that the combined thermomechanical treatment (TA₁HA₂), being within the present invention surely and always leads to a remarkable increase in the mechanical strength without negatively influencing the secondary properties (in some cases on the contrary improving some of them) such as ultimate elongation, stress corrosion tensile strength, fatigue strength, creep strength etc.

It is obvious that modifications and alternatives with equivalent character can be made while remaining within the spirit and scope of the invention.

What is claimed is:

1. A thermomechanical treatment process for heat treatable aluminum alloys selected from the group consisting of Al-Zn-Mg and Al-Zn-Mg-Cu systems comprising

submitting said alloys in preformed shape to a solution and quenching treatment (T) followed by a combination of plastic deformation and precipitation hardening including:

a first aging treatment (A₁) at a temperature between 60° and 200°C for times ranging from 2 to 50 hours,

a plastic deformation (H) of between 10 and 30 percent obtained by reducing the thickness of the wrought product and

a further aging treatment (A₂) at a temperature and for a time at least equal to the conditions employed in said first aging treatment.

2. The process of claim 12 wherein said second aging treatment (A₂) is carried out at a temperature between 60° and 230°C for times ranging from 2 to 120 hours.

3. The process of claim 12 wherein said combination of deformation and hardenings (A₁HA₂) is a cycle repeatable on the same alloy sample at temperatures and for times in the same range as those specified.
